DISPLAY WINDOW

William E. McCormick, New York, N. Y., assignor
to Invisible Glass Company of America, Inc.,
New York, N. Y., a corporation of Delaware

Application August 7, 1951, Serial No. 240,700

1 Claim. (Cl. 88—1)

1

This invention relates to display windows and particularly to those of the character shown and described in the patents to Brown, No. 1,911,881 and 2,003,735 wherein the window consists of one or more curved pane sections and associated elements so arranged that distracting reflections are nullified or rendered inconsequential.

The installation of windows constructed according to the above patents has been found expensive and time-consuming, due to the fact that display windows vary greatly in height, depth and width and therefore to secure the desired results, the curvature of the pane installed in each instance had to be varied to meet the requirements of such installation. This required the individual molding of each pane in the required curvature, and very often when errors or deviations from the measured dimension took place in the manufacture of the curved pane, the pane could not be used. In short, each pane installed was required to be "custom-made" and installed with the greatest of care and skill lest it fail to kill glare and reflections in the required manner.

With the knowledge of these facts, the present invention has for its object, the provision of a curved pane adapted for installation and use as set forth in said patents, said pane however, being of such shape so that it can be installed in various environments of considerable difference in size and proportions, yet the pane will in each instance and at normal eye level, eliminate reflections. With an arrangement as above described, it will be apparent that curved panes of this character may be kept in stock, supplied promptly for new installations or to replace breakages, with a minimum of delay, also, since all of the panes required for different installations are of the same curvature, a single mold for producing the pane is all that is required.

The invention will be more clearly understood by references to the accompanying drawing wherein the figure shown diagrammatically illustrates a pane curved according to the invention and installed to meet requirements.

In the drawing, the curved pane is indicated at 1, the same being supported at its lower end by the inner sill 2 and at its upper end by the heading 3. The outer sill designated at 4 has its interior surface 5 covered with velvet or other light-absorbing material tending to dissipate all reflections. The inclined reflecting trough is indicated at 6, the same being usually surfaced with a satin-finish plastic material or some equivalent material of similar characteristics.

2

The curvature of the pane 1 has been developed by curving the glass as a parabola with three radii. The curvature of the upper portion of the parabola, or that part of the curve located between the points shown at 7 and 8 has the longest radius, or that designated at 9. The next radius is that which defines the curve in the pane between the points 8 and 10, such radius being designated at 11. The lower portion of the curve, or that portion found between the points 10 and 12 is that indicated at 13.

For a pane having an approximate height of six feet, the longest radius, or that indicated at 9 would be 6'-5".

15 The second radius, or that indicated at 11 would be 4 feet, 7 inches, and the shortest radius indicated at 13 would be approximately 3 feet, one inch. In the development and installation of a curved pane of this character, combined with the baffle arrangement shown, the optimum sought is complete transparency without reflections when the glance of a person of normal height, standing before the concave side of the pane, is directed through the pane. With a pane curved as above described a sight level of from four feet nine inches to five feet ten inches produces complete transparency without reflections, and this in spite of the fact that in different installations the pane may be located at different positions in respect to the viewer.

20 For example, in the drawing the pane shown at 1 is located at a certain height and position according to the structure or frame of the window arranged for its installation. In the position shown at 1a, it will be noted that the pane is located so that it is farther from the spectator and that it has been swung so that its upper end is closer to a vertical line extended upwardly from its lower end than is the case with the pane shown at 1, wherein the upper end is much farther forwardly of its lower end.

25 In the pane installation shown at 1b, the pane has been swung about a horizontal axis to position it differently from the pane shown at 1 and at 1a. As 1c is shown an installation wherein the pane has been lowered and positioned with its upper end located forwardly to a substantial extent. The installation shown at 1d is a slight deviation from that shown at 1.

30 In the several positions of the pane, and which positions and many others are required by various differences and variations in window frame construction, similar viewing results are obtained when a three-radii pane of the character described is used. That is to say, that despite the changes in position of the curved pane, non-

reflecting results at normal eye levels will be obtained. It will thus be apparent that a universal curvature is present, capable of permitting a pane of the same bend to be installed to suit conditions and still appear invisible over a large variation of head and sill heights.

In the past, the curved panes had to be designed for each particular job, requiring the making of full-sized drawing lay-outs and an individual mold for the bending of the glass, which work usually required about sixty days. By the use of a pane of universal curve as herein described, a single mold will produce the panes; the panes may be raised or lowered and pivotally moved, within all reasonable limits, to meet specific installations, yet the pane remains invisible when viewed at normal viewing heights.

It will, of course, be understood that mirrors are arranged at the opposite ends of the glass pane, such mirrors being herein omitted for clarity in description.

Having described one embodiment of the invention, it is obvious that the same is not to be restricted thereto, but is broad enough to cover all structures coming within the scope 25 of the annexed claim.

What I claim is:

In a display window, a transparent pane having a surface of irregular curvature formed as three sections each having a radius of different 30 length, and merging imperceptibly into one another, the upper portion of a pane having a height of six feet, being formed with a curve having

a radius of approximately six feet, five inches, the second curve being located in the pane below the first curve and having a radius of approximately four feet and seven inches, and the third curve being located below the second curve having a radius of approximately three feet and one inch, the radii of the three curvatures thus decreasing in length from the upper curvature to the lower curvature, the curved surface areas 10 formed by the mentioned radii constituting a continuous surface formed around a horizontal axis to permit the pane to be fixed in various reasonable installation positions without developing reflections to the observer when viewed from the concave side at about normal eye level.

W. E. McCORMICK.
